APPARATUS FOR DRILLING WELLS

Manley L. Natland and Howard A. Taylor, Long Beach, Calif.; said Taylor assignor to Lester Callahan

Application October 25, 1946, Serial No. 705,610

15 Claims. (Cl. 255—72)

1

Our invention relates to well drilling and, more particularly to a novel drilling apparatus suited to obtain core sections during continued drilling and/or a residual or filamentary core upon withdrawal of the drilling bit for inspection, repair, or replacement.

The present invention contemplates cutting into the earth in an annular zone to leave a central core portion which is maximized in length by being progressively disintegrated into core particles, and it is an object of the invention to provide an improved drilling structure of the type shown in the copending application of Howard A. Taylor Serial No. 705,691, filed Oct. 25, 1946.

By the term "disintegrating," we have reference to a subdivision of the central core portion into core particles, irrespective of the size thereof. As pointed out in the application supra, such core particles may be relatively small sand-like or cutting-like particles, as when the core portion is substantially completely disintegrated, or they may be in the form of larger masses, hereinafter termed core sections, which are severed, broken, or otherwise removed from the central core portion, being of substantial size but representing more than a mere temporarily compacted mass of cuttings from a bit. Such core specimens give particularly valuable data concerning subterranean strata including geological age, slope and character of subterranean strata, etc.

The present invention contemplates that the core particles, resulting from the progressive disintegration of the central core portion during continued drilling, shall be discharged to the exterior of the drilling structure and preferably into a column of fluid moving upward in the well. For example, it is common practice to drill wells by use of a rotary bit during the time that a high-density drilling mud is forced into the zone of the cutters to carry upward in the well the cuttings. In the preferred practice of the present invention, the core particles are discharged into the rising drilling mud and, if of substantial size, can be separated therefrom at the top of the well to provide a continuous coring method giving valuable information as to subterranean strata during continued drilling. It is an object of the present invention to provide an improved drilling system for accomplishing this.

The invention also contemplates a drilling structure having a central passage to receive the central core portion. Disintegration of this core portion preferably takes place a substantial but

2

constant distance above the cutting elements, whereby the lower end of such a central passage contains a filamentary core. By use of the present invention, this core can be severed or detached from the earth's strata preparatory to lifting the drilling structure, and can be carried upward with the drilling structure when withdrawn for inspection, repair, or replacement. It is an object of the present invention to provide an improved apparatus for obtaining a residual filamentary core from a heavy duty drilling structure when withdrawn from the well.

Another object is to provide an easily removable internal structure which carries such a residual core, this internal structure being designed to facilitate removal of the residual core therefrom.

Further objects and advantages of the invention will be evident from the following description of exemplary embodiments.

Referring to the drawings:

Fig. 1 is a utility view, showing diagrammatically well drilling equipment employing one form of the invention;

Fig. 2 is a vertical cross-sectional view of the drilling structure of Fig. 1;

Fig. 3 is a horizontal sectional view, taken along the line 3—3 of Fig. 2; and

Fig. 4 is a bottom view of the drilling structure of Fig. 2.

Referring particularly to Fig. 1, the invention is shown as being used to drill a well or bore 10 in the earth to penetrate strata suggested at 11, a portion of the well being shown cased by a casing 12. A derrick floor 13 carries the usual rotary drilling table 14 turned by a suitable power source, not shown, to rotate a drill column 16 formed of sections of drill pipe 17 coupled by joints 18. At the upper end of the drill column 16 is the usual swivel 20, the lowering of the drill column being controlled by the position of a travelling block 21 connected to the swivel through a bail 22. The upper end of the drill column is supplied with a fluid, such as a high-density drilling mud, to move downward therethrough and carry the cuttings upward in the well. This fluid may be supplied at high pressure and very considerable volume through hose 23 and pipe 24 by a circulating pump 25.

The drilling structure 30 of the invention is secured to the lower end of the drill column 16, as by a collar 31. Essentially, the drilling structure 30 includes a bit 32 and a drive unit 33, here shown as a drill collar or sub 34 detachably connected to the collar 31.

The bit 32 is shown as including a body 35 having a depending head 36 having a central opening 37. The body 35 has two diametrically opposite arms 38 and two additional diametrically opposite arms 39. In the space between each of the arms 38 and the depending head 36 is a peripherally-toothed frusto-conical gage cutter 40 rotating on a suitable pin, not shown, extending between the arms and the head. Similarly, in the space between each arm 39 and the depending head 36 is a peripherally-toothed frusto-conical mill cutter 41, similarly journaled on a pin, not shown. The innermost portions of the two mill cutters 41 are preferably spaced a distance substantially corresponding to the diameter of the central opening 37, as best shown in Fig. 4. As the bit 32 turns, the cutters 40, 41 rotate on their respective pins and revolve relative to the central axis A—A of the bit, which axis coincides with the axis of the central opening 37. During rotation of the bit 32, the cutters 40 and 41 cut into the earth in an outer annular zone, the gage cutters 40 deepening the bore in the outer portion of such zone and determining the well diameter, while the mill cutters 41 cut into the earth in the inner portion of such outer annular zone and, in the absence of other cutting elements, would leave a core portion of a diameter substantially equal to that of the central opening 37.

In this embodiment of the invention, additional core-cutting means is provided, comprising a core-cutting element 45 detachably extending into the central opening 37. The lower end of this core-cutting element provides teeth 46 which terminate opposite or somewhat above or below the lower portions of the cutters 40, 41. These teeth are disposed around a central passage 47 of the core-cutting element 45 and cut into the earth in an inner annular zone within the previously mentioned outer annular zone to leave a central core portion 50 which extends upward in the central passage 47.

The core-cutting element 45 is detachably connected to the body 35 in any suitable manner. As shown, the lower end of the depending head 36 provides diametrically opposite cavities 51, and the core-cutting element 45 carries arms 52 extending snugly therein and retained by pins 53. The upper end of the core-cutting element 45 comprises a neck 54 extending into the central opening 37.

The inner surface of this opening 37 preferably cooperates with the outer surface of the neck 54 to provide a downwardly-directed passage means for jetting drilling mud or other fluid at high velocity toward the bottom of the well, preferably near the junction of the inner and outer annular zones, respectively penetrated by the teeth 46 and by the cutters 40, 41. In the preferred construction, the inner wall of the central opening 37 is cylindrical and engages snugly the outer wall of the neck 54. However, this outer wall provides longitudinal grooves around its periphery, these grooves facing the wall of the central opening 37 and cooperating therewith in defining a plurality of passages 55, best shown in Fig. 4. The upper ends of these passages communicate with a chamber 56 of the bit so that the drilling mud or other fluid in this chamber under high pressure will be jettied downward through the passages 55 to impinge on the floor of the well and aid the drilling operation, either by a hydraulic cutting, similar to that effected in hydraulic mining, or by directing the cutting fluid in the immediate vicinity of the teeth 46.

to facilitate the cutting action and remove cuttings. Similarly, high-pressure drilling mud or other fluid may flow from the chamber 56 through four small passages 57, respectively directed toward the upper portions of the cutters 40 and 41 to wash the cuttings therefrom and facilitate the cutting action thereof. As in the usual practice, such drilling mud or other fluid rises in the well 10 around the drilling structure 30, as indicated by arrows 58, carrying the cuttings to the surface of the ground where the fluid and its associated cuttings discharge through a pipe 59 into a sump 60.

The sub 34, forming the drive unit of this embodiment of the invention, provides an externally-threaded neck 61 threaded into a cavity 62 of the bit. The uppermost end of the sub 34 is suitably connected to the collar 31 or to some other element of the drill column 16. As shown, the upper end of the sub includes a threaded neck 63 threadedly received by the collar 31. In the present invention, the sub 34 is preferably formed as a massive tubular member relatively easy to fabricate and providing a longitudinal passage 64 through which mud or other fluid may flow to the chamber 56 under high pressure.

The invention provides a means for progressively disintegrating the central core portion 50 at a position within the drilling structure 30, and preferably within the drive unit 33. The preferred embodiment of the present invention contemplates the use of a structure for subjecting the central core portion 50 to bending stresses, e. g., by providing an axially curved core passage means along which the central core portion 50 is moved to break core sections from the central core portion. A preferred structure of this type is best shown in Fig. 2.

Referring particularly to Fig. 2, the central passage 47 is counterbored to receive the lower end of a tubular member 65 traversing the chamber 56 and of an internal size slightly larger than the central core portion 50. In this respect, the central passage 47 may be stepped in size at an intermediate position, as suggested in Fig. 2, and its lower end may be of slightly smaller diameter than the interior of the tubular member 65.

Telescoping with the upper end of the tubular member 65 and coaxial with the axis A—A is a straight tubular member 67 cooperating with the tubular member 65 to define a core-receiving passage 68 which is preferably somewhat larger in diameter than the core portion 50. If desired, the lower end of the tubular member 67 may be slightly enlarged to receive the tubular member 65, as shown, it being desirable to employ a telescoping connection between the tubular members 65 and 67. The junction between these members can be relatively snug or somewhat loose. In the latter event some of the drilling mud or other cutting fluid may move from the chamber 56 between the telescoping members and into the core-receiving passage 68. Such drilling mud or other fluid reaches the chamber 56 by flow through an annular fluid-conducting space 69 within the longitudinal passage 64 outside the tubular member 67.

The drill collar or sub 34, comprising the drive unit in this embodiment, is usually relatively long, typically 7 ft. or more, whereby a relatively long section of the core portion 50 may be contained in the core-receiving passage 68.

The invention contemplates the use of a novel disintegrating means for disintegrating the core portion rising above the upper end of the tubu-

lar member 67. It contemplates also that the upper end of the tubular member 67 shall be removably connected to such disintegrating means so that the tubular member 67, with its retained core portion, can be withdrawn from the drill collar 34 and this core portion subsequently removed from the tubular member.

As best shown in Figs. 2 and 3 the drive unit, here shown as the drill collar or sub 34, provides an opening 78 which extends from the longitudinal passage 64 to the exterior of the drill collar. In this opening is mounted a box-like exit unit 72 shown as comprising side walls 73 with a heavy bottom wall 74 and a sloping or curved wall 75, extending therebetween and welded thereto. The curved wall 75 extends from a position above the rising core portion 50 to a position within the opening 78. The walls of the exit unit 72 cooperate in defining a chamber 76 having an exit opening 77 shown as substantially rectangular in shape and opening on the side of the drill collar or sub 34. The box-like exit unit 72 may be integral with or suitably fixed to the drill collar or sub 34 and should not completely block the longitudinal passage 64 so as to provide a passage means for downward flow of the mud or cutting fluid to the fluid-conducting space 69. As shown, this exit unit is separately assembled and then welded in the opening 78, as by being welded around a peripheral portion 78.

The upper end of the tubular member 67 is removably connected to the exit unit 72 as by being slidably extended into or threaded in an opening 80 of the bottom wall 74. The threaded connection is illustrated and, to facilitate unscrewing of the tubular member 67, its lower end provides notches 81 into which a suitable tool can be placed after the bit 32 has been unscrewed. To guide the tubular member 67 in its attachment and to substantially center it in the longitudinal passage 64, we prefer to use a spider-like guide shown as including upper and lower sets of radial arms 82 extending from the tubular member 67 into close adjacency to the inner wall of the longitudinal passage 64.

As the drilling structure 30 rotates, the bit 32 will cut into the earth in an annular zone and the upstanding core portion 50 will rise in the core passage 68, usually while still affixed to the earth. This core portion will be stationary relative to the now-turning exit unit 72. However, if the core portion 50 has, for some reason, been severed from the earth it will rotate with the drive unit 33. In either event, as soon as the upper end of the core portion engages the curved wall 75 it will be disintegrated, as by being subjected to bending stresses. Whether or not the core portion is rotating with the drive unit, forcing same against the curved wall 75 will apply a bending stress in a direction toward the exit opening 77. Depending partially upon the character of the core portion 50, this disintegration will be into core particles of a size varying from minute subdivisions of the core portion to sizable core sections. In drilling through hard formations, sizable chunks forming the core sections are broken from the core portion 50, usually along natural cleavage planes, one such core section being indicated at 83. Such core sections or particles are formed, in the present invention, in the relatively large chamber 76 and are discharged into the rising mud stream through the relatively large exit opening 77, thus minimizing erosive action such as would take place if the core section 75

83 were gradually extruded sidewise from the drill collar or sub 34.

The core particles, whether they be small or in the form of core sections, are carried upwardly to the surface of the ground with the rising mud stream and can be discharged through the pipe 59 onto a screen 85. Adhering mud can be washed therefrom by a spray 86. Such core sections give an accurate indication of the character of the formation being penetrated, the slope of this formation, and much other information apparent to a skilled geologist or paleontologist as to the age and oil-bearing possibilities of the strata being penetrated.

15 One of the important features of the present invention is that a residual core portion remains in the core passage 68 when the bit is raised for inspection, repair or replacement. As pointed out in the application supra, various means may be used for severing the central core portion from the earth, preferably at a position adjacent the bottom of the bore, preparatory to removal of the bit from the well. Such severance can be effected by stopping the circulation of drilling mud 20 while continuing to rotate the bit rapidly, often with substantially increased cutting pressure applied to the bit. This "burns in" the core portion, causing it to wedge tightly in the central passage 47 of the bit and causing severance from the 25 earth's strata. Thereafter, the residual core portion can be raised to the surface of the ground with the bit.

When it is desired to remove this residual core portion from the drilling structure 30 the bit 32 30 is unscrewed from the drive unit 33 and the tubular member 65 drawn from its telescoping relationship with the tubular member 67. A suitable tool is inserted in the notches 81 and the entire tubular member 67 unscrewed from the opening 80 of the bottom wall 74. The residual core portion is then forced from the tubular member 67. The straightness of this tubular member facilitates the removal of the core portion without breakage. In addition, this residual core portion 40 can be made substantially as long as desired due to the fact that the tubular member 67 is not limited in length by bends or structural features.

Various changes and modifications can be made without departing from the spirit of the invention as defined in the appended claims.

50 We claim as our invention:

1. Apparatus for drilling into the earth with a rotary bit providing means for cutting into the earth in an annular zone to leave a central core portion, said apparatus including: a drive unit adapted to be detachably connected to said bit; a tubular core-receiving member in said drive unit and providing a lower end adapted to receive said core portion as drilling progresses and an upper end having an opening adapted to expel said core portion; a wall fixed relative to said drive unit; connecting means for removably connecting said upper end of said core-receiving member to said wall; and means above said wall for disintegrating said core portion.

2. An apparatus as defined in claim 1, in which said tubular core-receiving member is straight and in which said fixed wall provides an opening of a size to receive said upper end of said core-receiving member, said core-receiving member being withdrawable from the lower end of said drive unit when said bit is detached from said drive unit and said core-receiving member is released by said connecting means.

3. Apparatus for drilling into the earth with a

rotary bit providing means for cutting into the earth in an annular zone to leave a central core portion, said apparatus including: a drive unit providing means for detachably connecting same to said bit; a tubular core-receiving member in said drive unit and providing a lower end adapted to receive said core portion as drilling progresses and an upper end having an opening adapted to expel said core portion and having a threaded portion; and a box-like exit unit carried by said drive unit and providing an exit opening communicating with the exterior of said drive unit and providing an entrance opening threadedly receiving said threaded portion of said core-receiving member to permit unscrewing and withdrawal of said core-receiving member from the bottom of said drive unit upon disconnection of said bit and said drive unit.

4. An apparatus as defined in claim 3, in which said box-like exit unit includes a lower wall providing said threaded entrance opening, said exit unit including also an angled wall engageable by said core portion to disintegrate same and produce core particles which are guided to said exit opening.

5. Apparatus for drilling into the earth with a rotary bit providing means for cutting into the earth in an annular zone to leave a central core portion, said apparatus including: a tubular drive unit for said bit, said drive unit including a longitudinal passage for conducting to said bit a cutting fluid; a box-like exit unit fixed to said drive unit and extending inwardly into said longitudinal passage from one side of said tubular drive unit to leave a portion of said longitudinal passage open for conducting said cutting fluid, said exit unit including a lower wall extending inward from said one side of said tubular drive unit; a tubular core-receiving member within said longitudinal passage to provide an annular space for conducting said cutting fluid toward said bit, said core-receiving member providing a lower end adapted to receive said core portion as drilling progresses and providing an upper end from which said core portion is expelled; and means for detachably connecting said upper end to said lower wall with said upper end in open communication with the interior of said exit unit to discharge said core portion thereinto, said exit unit providing an exit opening for the material of said core portion.

6. An apparatus as defined in claim 5, in which said exit opening of said exit unit communicates with the exterior of said drive unit, and in which said exit unit includes an angled wall extending angularly from a position above said lower wall to said exit opening to be contacted by said core portion in a manner to disintegrate same and produce core particles, said core particles being discharged from said exit opening.

7. An apparatus as defined in claim 5, in which said drive unit includes a side opening communicating with the exterior of said drive unit and of larger size than said exit opening of said exit unit, and in which said box-like exit unit provides a first portion of a size to fit in said side opening and a second portion extending into said longitudinal passage, said first portion of said exit unit being secured in said side opening as the exclusive support for said exit unit, said exit unit being secured in said side opening by being welded to said drive unit adjacent the periphery of said side opening.

8. Apparatus for drilling into the earth with a rotary bit providing means for cutting into the earth in an annular zone to leave a central core

portion, said apparatus including: a drive unit providing means for detachably connecting same to said bit, said drive unit including a longitudinal passage and a sidewardly-facing exit opening; a relatively massive wall member secured to said drive unit and extending substantially transversely of said longitudinal passage, said wall member incompletely blocking said longitudinal passage and providing walls bounding a passage means through which cutting fluid may flow toward said bit; a tubular core-receiving member adapted for insertion into said longitudinal passage of said drive unit from its lower end to cooperate with said drive unit in providing a fluid-conducting space communicating with said passage means to conduct said cutting fluid to said bit, said tubular core-receiving member providing a lower end adapted to receive said core portion as drilling progresses and an upper end providing an opening adapted to expel said core portion; interengaging means on the upper end of said core-receiving member and said massive wall member for removably securing said core-receiving member to said relatively massive wall member, said interengaging means being releasable by movement of said lower end of said core-receiving member relative to said drive unit; and wall means providing a chamber communicating between said opening of said upper end of said core-receiving member and said sidewardly-facing exit opening of said drive unit to conduct the material of said core portion from the former to the latter.

9. An apparatus as defined in claim 8, in which said relatively massive wall member provides an opening of sufficient size to receive said upper end of said tubular core-receiving member, and in which said interengaging means for removably securing said core-receiving member to said wall member includes means for connecting said upper end in fluid-tight relationship with said wall member at the junction of said upper end and said wall member.

10. Apparatus for drilling into the earth with a rotary bit providing means for cutting into the earth in an annular zone to leave a central core portion, said apparatus including: a drive unit including means for connecting same to said bit, said drive unit including a longitudinal passage and a sidewardly-facing exit opening extending from said longitudinal passage to the exterior of said drive unit; a tubular core-receiving member of a size to extend along said longitudinal passage and to cooperate with said drive unit in providing a fluid-conducting space for conducting cutting fluid to said bit, said tubular core-receiving member providing a lower end adapted to receive said core portion as drilling progresses and an upper end having an opening adapted to expel the material of said core portion; an exit unit secured to said drive unit and extending into said longitudinal passage from the vicinity of said exit opening of said drive unit, said exit unit including walls defining a passage means for conducting said cutting fluid past said exit unit to said fluid-conducting space, said exit unit including an opening of a size to receive said tubular core-receiving member, said exit unit including a chamber extending sidewardly from said opening of said upper end of said core-receiving member to said sidewardly-facing exit opening of said drive unit to conduct the material of said core portion sidewardly from said drive unit; and means for removably securing said tubular core-receiving member to said exit unit with said upper end of

said core-receiving member in said opening of said exit unit.

11. An apparatus as defined in claim 10, in which said means for removably securing said tubular core-receiving member to said exit unit includes interengaging means on said core-receiving member and said exit unit and engageable when said core-receiving member is inserted into the lower end of said drive unit, said interengaging means being disengageable by movement of the lower end of said core-receiving member relative to said drive unit.

12. An apparatus as defined in claim 11, in which said lower end of said tubular core-receiving member is positioned within the lower end of said drive unit when said interengaging means are engaged, and in which said lower end of said tubular core-receiving member provides tool-receiving means facilitating disengagement of said interengaging means to release said core-receiving member with its contained core portion.

13. Apparatus for drilling into the earth with a rotary bit providing means for cutting into the earth in an annular zone to leave a central core portion, said apparatus including: a drive unit including means for detachably connecting same to said bit, said drive unit including a longitudinal passage and a sidewards-facing exit opening; a tubular core-receiving member of a size to extend along said longitudinal passage and to cooperate with said drive unit in providing a fluid-conducting space for conducting cutting fluid to said bit, said tubular core-receiving member providing a lower end adapted to receive said core portion as drilling progresses and an upper end having an opening adapted to expel the material of said core portion; and means for removably suspending said tubular core-receiving member in said longitudinal passage, said means including an exit unit secured to said drive unit and extending into said longitudinal passage from the vicinity of said exit opening of said drive unit, said exit unit including a relatively massive wall, said means including interengaging means on said relatively massive wall and said core-receiving member to be moved into engagement to suspend said core-receiving member in said longitudinal passage, said exit unit including a chamber extending from said opening of said upper end of said core-receiving member and sidewards to

said exit opening of said drive unit to conduct the material of said core portion sidewards from said drive unit.

14. Apparatus for drilling into the earth with a rotary bit providing means for cutting into the earth in an annular zone to leave a central core portion, said apparatus including: a tubular drive unit for said bit, said drive unit including a longitudinal passage for conducting to said bit a cutting fluid; a box-like exit unit carried by said drive unit and extending inwardly into said longitudinal passage from one side of said tubular drive unit to leave a portion of said longitudinal passage open for conducting said cutting fluid, said exit unit including a pair of side walls, a bottom wall extending between said side walls and a curved wall extending between said side walls to define a chamber having an exit opening communicating with the exterior of said drive unit, said curved wall curving upwardly and outwardly from said bottom wall to said exit opening; and a tubular core-receiving member within said longitudinal passage to provide an annular space for conducting said cutting fluid toward said bit, said core-receiving member providing a lower end adapted to receive said core portion as drilling progresses and an upper end communicating with the interior of said exit unit to discharge said core portion thereinto.

15. An apparatus as defined in claim 5, including means for detachably connecting the upper end of said core-receiving member and said bottom wall to permit removal of said core-receiving member from said drive unit while containing said core portion.
